UNITED STATES PATENT OFFICE

94,613

DESIGN FOR AN ASH TRAY

Morgan J. Lewis, Philadelphia, Pa.

Application December 7, 1934, Serial No. 54,330

Term of patent 3½ years

To all whom it may concern:

Be it known that I, Morgan J. Lewis, a citizen of the United States of America, residing at Philadelphia, county of Philadelphia, State of Pennsylvania, have invented a new, original, and ornamental Design for an Ash Tray, of which the following is a specification, reference being had therein to the accompanying drawing.

In the accompanying drawing—

Fig. 1 is a perspective view showing my new design for an ash tray.

Fig. 2 is a longitudinal sectional view thereof.

I claim:

The ornamental design for an ash tray, as

MORGAN J. LEWIS.
